UNITED STATES PATENT OFFICE.

JULIUS C. GOODWIN, OF PHILADELPHIA, PENNSYLVANIA.

SEWING-MACHINE.

No. 884,579.

Specification of Letters Patent.

Patented April 14, 1908.

Application filed September 14, 1905. Serial No. 278,428.

To all whom it may concern:

Be it known that I, JULIUS C. GOODWIN, a citizen of the United States, residing at Philadelphia, in the county of Philadelphia and 5 State of Pennsylvania, have invented certain new and useful Improvements in Sewing-Machines, of which the following is a specification.

My invention relates to improvements in 10 that class of sewing machines employed in the manufacture of shirts, overalls and underwear and is particularly adapted to the hemming of sleeves and like portions of a garment which cannot be satisfactorily 15 stitched by machines of the ordinary household type.

My invention embodies details of construction which enables the machine to be run at a high rate of speed with freedom from 20 noise and vibration common to this class of machines.

My invention will be more fully understood by reference to the accompanying drawings forming part of this specification 25 and wherein:

Figure 1 illustrates a side elevation of a machine constructed in accordance with my invention. Fig. 2 represents a longitudinal section of the same taken on a line 2—2 as indicated in Fig. 1. Fig. 2^x represents a detached plan view of a portion of the machine showing the arrangement of the throat-plate. Fig. 3 shows a front elevation of the machine. Fig. 4 illustrates a detached perspective view 35 of the looper slide and loopers, and Fig. 5 shows a detached perspective view of the feed-bar and the bell-crank lever and connections for raising and lowering the same. Fig. 5^x shows a slightly modified form of 40 bell-crank-lever, the view otherwise being the same as Fig. 5.

Referring now to the reference letters of the drawings, A denotes the base of the machine which is provided with bearing A¹, A¹, 45 to receive a driving shaft B. This driving shaft is furnished with a hand wheel B¹, a grooved pulley B², and a number of eccentrics B³, B⁴, B⁵, B⁶ and B⁷ from which motion is obtained to operate the various parts of 50 the machine in a manner hereinafter described.

The base of the machine has projecting upward and outward from it a curved arm A², which is provided with bearings A³, A³, 55 for the reception of a needle bar C, and bearings A⁴, A⁴, to receive a presser-bar D. The

base has also projecting outward from it directly under the arm A² another arm A⁵, which is hollowed out to receive the lower stitch forming mechanism and is provided at 60 or near its free end with a throat plate A⁶.

The upper stitch forming mechanism is controlled by the eccentric B³, through the following line of connections. On the said eccentric is a ring C¹, upon which is fulcrumed 65 the forked end of a lever C², which projects upward and is provided with a bearing C³, forming a socket for the ball end of the lever C⁴. The last mentioned lever is connected to a longitudinal shaft C⁵ fitted to bearings 70 b⁵, b⁵, on the arm A², which shaft is provided at its forward end with a lever C⁶, connected to a link C⁷, and this in turn is pivoted to the side of a collar C⁸, mounted upon the needle bar C, containing two needles c and c¹. The 75 presser bar D, is provided with the conventional presser foot D¹, which is normally held down by means of a leaf spring S, one end of which is fastened by a screw d, to a lug d¹, on the arm A², while the other end bears 80 upon a lug d² on the presser bar D. The pressure of the spring S upon the presser bar may be increased or diminished by means of a set screw D², which is threaded in a lug d³, on the machine and bears upon the spring. 85 The presser bar and its parts may be raised at will by means of a cam D³, which as shown in Fig. 1 of the drawings is secured upon the presser bar by means of a pin d³. The goods upon which a seam is to be stitched is fed 90 forward over the arm A³, by means of a feed plate E, which is controlled by the two cams B⁶ and B⁷ the former of which imparts a forward and backward movement to the feed plate while the latter raises and lowers the 95 same and consequently brings the teeth of the plate into and out of contact with the fabric to be acted upon.

The feed plate E, is connected to or as shown in Figs. 1 and 2 may form a part of a 100 bar E¹, which for the purpose of adjusting the longitudinal movement of said feed plate is connected to the upper end of a segment E², which has its lower end fulcrumed to the frame of the machine at a point a³. The segment E² is provided with a slot e² to receive a stud E³, which holds the segment in working engagement with an eccentric rod E⁴, operated upon by the eccentric B⁶. The raising and lowering of the feed plate as before 110 stated is controlled by the eccentric B⁷, which is operatively connected to one end of

an eccentric lever E^5 , whose opposite end is fulcrumed to the short arm of a bell crank lever E^6 , which has a bearing in the arm A^3 and by means of links e^6, e^6 , has its long arm connected to the feed plate E . The looper F , which forms the essential feature of the lower stitch forming mechanism, constitutes a bell crank F^1 provided with needle like loopers f, f , which as is well known in the art intercept the loops brought down and formed upon the needles c and c^1 . The bell crank F^1 of the looper F , is mounted upon a slide F^2 , by a screw f^1 , which forms its fulcrum and the bell crank is operated by having the arm f^2 fulcrumed to an eccentric rod F^3 , which in turn is fulcrumed at a point f^3 to an eccentric strap F^4 controlled by the cam B^5 . The slide F^2 , is guided in a slot a^4 , in the forward end of the arm A^3 , and is operated from the eccentric B^4 by an eccentric lever F^5 , which is operatively connected to the slide by a screw f^5 .

Having described my invention what I claim and desire to secure by Letters Patent 25 is:

1. A sewing machine comprising a main shaft, a feed bar, a segment fulcrumed at one end to the machine frame and connected at its other end to the feed bar, an eccentric, an eccentric rod adjustably secured to the segment intermediate its connections with the

feed bar and the machine frame for varying the stroke of the feed bar, a bell crank lever having one of its arms connected to the feed bar, and a horizontally reciprocating rod 35 connected to the other arm of the bell crank lever, whereby motion is imparted to the bell crank lever for raising and lowering the feed bar.

2. A sewing machine comprising a main 40 shaft, a horizontally reciprocating feed bar, a segment fulcrumed at one end to the machine frame and connected at its other end to the feed bar, an eccentric, an eccentric rod adjustably secured to the segment intermediate its connections with the feed bar and the machine frame for varying the stroke of the feed bar, a bell crank lever having one of its arms connected to the feed bar, a horizontally reciprocating rod connected to the 50 other arm of the bell crank lever, whereby motion is imparted to the bell crank lever for raising and lowering the feed bar, and a casing for all of said parts having an opening therein through which access may be had for adjusting the eccentric rod.

In testimony whereof I affix my signature in presence of two witnesses.

JULIUS C. GOODWIN.

Witnesses:
